UNITED STATES PATENT OFFICE.

C. DIEDRICH JANSSEN AND WILLIAM DE VOE, OF TORRINGTON, CONN.

ATTACHMENT FOR SQUARES.

SPECIFICATION forming part of Letters Patent No. 357,771, dated February 15, 1887.

Application filed March 13, 1886. Serial No. 195,134. (No model.)

To all whom it may concern:

Be it known that we, C. DIEDRICH JANSSEN and WILLIAM DE VOE, citizens of the United States, and residing at Torrington, in the 5 county of Litchfield and State of Connecticut, have invented certain new and useful Improvements in Drafting-Instruments, of which the following is a specification.

Our invention is a drafting-tool consisting 10 of a block provided with a slot and adapted to receive a pointer or stylus, and to be used in connection with a bar to perform operations ordinarily requiring the use of angles and compasses.

15 In the drawings, Figure 1 is a side view of our improved drafting-tool; Fig. 2, a perspective view showing the same applied to a steel square; Fig. 3, a perspective view showing the application in connection with a two-foot rule; 20 Fig. 4, a view illustrating the manner of using a series of the tools; Fig. 5, a view showing the manner of using the device as a plumb-bob.

The device consists, essentially, of a block, A, having a recess, a , extending laterally into 25 one side, and a threaded socket, x , and a set-screw, B, extending through a threaded opening, y , at the end, so as to enter the recess. To the socket x is adapted the threaded end of a stylus, drafting pencil or pen, or other tool. 30 One or more of the devices thus constructed is applied to a square, flat rule, or other bar, D, so that the recess a will receive the edge of the said bar, and the device is then secured in its position by turning the set-screw B so as 35 to clamp it in place.

When the block A alone and without the stylus is used, it will serve as a stop to limit the position of the bar—as, for instance, in Fig. 2, there are two blocks applied to a steel square 40 in such manner that when they bear against the edge of a board, X, the edge of the square will be at an angle to the edge of the board, and a series of lines, $x' x'$, may be scored or drawn upon the face of the board parallel to each 45 other by drawing a pencil or stylus along the edge y of the square, and sliding the latter from time to time along the board, with the blocks A A bearing against the edge. It will be evident that the angle at which the lines x 50 are drawn may be altered by varying the position of one or the other of the blocks.

Another application of the device is shown in Fig. 3, in which the bar consists of an ordinary two-foot rule, and the blocks are applied thereto near the opposite ends, each block 55 carrying a stylus or pointer, J, one of which serves as a center or pivot, around which the other is carried by swinging the rule so as to score a curve or circle upon the surface to be marked.

In Fig. 4 is illustrated a series of devices applied to a single bar, four of the blocks being provided with short pointers, while each end block has a long pointer, which serves as a guide bearing against the edge of the board, 65 which is readily scored in parallel lines by drawing the bar and the part supported thereby over the surface of the same.

Where it is desired to produce a more legible mark, a pencil or drawing-pen may be substituted for the stylus J.

It will be seen that the above-described device, while cheaply constructed and easily applied to any bar, may be readily made the means of economically performing operations 75 ordinarily requiring the use of expensive drafting-tools.

In Fig. 5 another application of the device is shown, in which a metallic filling-piece, b, is adapted to the recess a , and a hole is drilled 80 through the set-screw B for a line, v, the device then forming a plumb-bob.

We are aware that it has been proposed to apply to a square a longitudinally-slotted block having at one end a set-screw entering 85 the slot, so as to secure the block adjustably on the square, and having at the other end a fixed pointer. Such a construction, however, is limited in its use, as it can be applied to one arm only of a square, and cannot be used as a 90 stop, nor can other tools be substituted for the pointer. We are also aware that it has been proposed to use a U-shaped piece of sheet metal having an integral pointer and a set-screw, so as to be placed at any point on a square or 95 rule; but such a device cannot be used as an adjustable stop and the pointer cannot be replaced by other tools. Our device, however, is distinguished from the above-mentioned devices in that we use a block having a lateral 100 recess in one side, a set-screw in one end and entering the recess, and a threaded socket at

the other end for the reception of tools. The lateral recess in the block adapts it to be applied at any point on a rule or square and project laterally above and below the same, and 5 thereby form an adjustable stop, the operation of which is apparent from Fig. 2 of the drawings.

Without limiting ourselves to the precise construction and arrangement of parts shown, 10 we claim—

1. A block, A, having a recess extending transversely into one side and a set-screw, B, extending into one end of the block and entering said recess, whereby the block may be 15 placed and secured on the edge of a rule or square at any point within the length and irrespective of the width thereof and project at right angles to said rule or square to form an adjustable stop, substantially as described.
- 20 2. A block, A, having a recess extending transversely into one side to receive the edge

of a rule or square, a set-screw, B, on one end and entering the recess, and a threaded socket in the opposite end for receiving a removable pointer, stylus, or other tool, substantially as 25 described.

3. The combination, with a rule, of one or more blocks, A, having set-screws B at one end, removable pointers J, and transverse recesses entered by the set-screws and adapted 30 to receive the edge of the rule, whereby the blocks will project at right angles to the same, substantially as described.

In testimony whereof we have signed our names to this specification in the presence of 35 two subscribing witnesses.

C. DIEDRICH JANSSEN.
WILLIAM DE VOE.
